UNITED STATES PATENT OFFICE.

EMILE L. A. CUREAU, OF EAST ORANGE, NEW JERSEY.

SHADE-FIXTURE.

SPECIFICATION forming part of Letters Patent No. 704,816, dated July 15, 1902.

Application filed May 31, 1901. Serial No. 62,472. (No model.)

To all whom it may concern:

Be it known that I, EMILE L. A. CUREAU, a citizen of the United States, residing at East Orange, in the county of Essex and State of New Jersey, have invented certain new and useful Improvements in Shade-Fixtures; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to brackets for supporting window-shade rollers; and the objects of the invention are to provide a bracket which can be readily fastened in a permanent position on the window-frame and afterward adjusted to suit different lengths of window-shade rollers, to secure a firm and rigid construction and one which can be securely clamped in its various positions by simple and easily-operated means, to secure a bracket which will support rollers for both outer and inner shades where it is desirable to use double shades and to enable both such supports to be simultaneously adjusted to different positions, and to obtain other advantages and results, some of which may be referred to hereinafter in connection with the description of the working parts.

The invention consists in the improved shade-roller bracket and in the arrangements and combinations of parts of the same, all substantially as will be hereinafter set forth, and finally embraced in the clauses of the claim.

Referring to the accompanying drawings, in which like letters of reference indicate corresponding parts in each of the several figures, Figure 1 shows in elevation the upper part of a window to which my improved bracket is applied. Fig. 2 is an end view of the bracket as on line x , Fig. 1. Fig. 3 is a view looking at the opposite or inner end of the bracket. Fig. 4 is a horizontal section as on line y , Fig. 1, and showing in outline both inner and outer shade-rollers in position; and Fig. 5 is a detail perspective view of a certain cam-roller hereinafter described.

In said drawings, a indicates a window-

frame of any usual form or construction, and b a window-sash sliding therein.

$c c$ indicate brackets of my improved construction applied one each side of the window-frame in the usual position to support the opposite ends of a shade-roller, said brackets being made, it will be understood, in pairs of rights and lefts accordingly. Each bracket comprises a sheet-metal arm d , adapted to lie flat against one of the opposite inwardly-facing sides or jambs of the window-frame, which are perpendicular to the sash b , and be firmly secured thereto, as by screws d' . The end of this arm is adapted to project beyond the face of the window-frame into the room, as shown in Fig. 4, and is bent substantially at right angles, as at e , to form a slideway or plate f , parallel to the face of the window-frame and having at its upper and lower edges lugs $f' f''$, bent away from the arm d at right angles to the plate f . Between said lugs and lying flat against the slide-plate f is adapted to stand in edgewise vertical position a sheet-metal slide g , which carries supports $l j$ to pivotally receive the shade-rollers. This slide is held in place against the slide-plate f by a cam-roller h , pivoted at its upper and lower ends in the lugs $f' f''$. Said ends, which lie pivotally in the lugs, are reduced, as at h' , and are disposed eccentrically with reference to the body of the roller, so that when said roller is turned by a thumb-piece i at one of its ends the roller is caused to jam forcibly against the slide g or lie loosely away from the same, according as it is turned. Said eccentric roller being pivoted or fulcrumed upon the lugs $f' f''$ of the supporting-arm d at the opposite sides of the slide g and extending across the front of the said slide not only serves as a fastener, but as a holder by which the said slide is held from detachment from its said supporting-arm d , while free to slide on said arm, and the thumb-piece at one end of the roller thus disposed and operating permits access of the fingers and does not interfere with or prevent a close arrangement of the curtain in front of said slide, as will be understood. At that end of the slide which lies in front of the window-frame, a little to one side of the window, the same is bent forward away from the stem d at right angles, as at j , and provided at its

end with a bearing j' to receive the shade-
roller k , as shown in Fig. 4. The other end
of the slide g , at the opposite side of the stem
 d , carries a sliding arm l , which projects from
5 the slide g toward the window and has at its
end a bearing for the roller m of an outer
shade. Said arm l is bent at right angles at
its end next the slide to form a base n to be
seated against the slide, said base having up-
10 per and lower ears n' n^2 projecting over the
edges of the slide. In said ears is pivoted, at
the front side of the slide g , a cam-roller o , similar
in every respect to the one, h , above de-
scribed and by means of which the arm l can be
15 tightened or clamped in any desired position
on the slide. The arm l preferably extends
downward from the slide g , as clearly shown
in Figs. 2 and 3, so as to bring the roller m
20 of the outer shade sufficiently below the top
of the window-frame even when the brackets
are applied high upon the frame.

In use it will be noted the brackets can be
employed for either outside or inside shades
alone or for both together and not only per-
25 mits independent adjustment of the arms j l
for such shades, but enables the arms when
two shades are used together to be simulta-
neously adjusted.

Having thus described the invention, what
30 I claim as new is—

1. A shade-roller bracket, comprising an
arm d , adapted to project from the window-
frame and providing a plate f , adapted to lie
parallel to the window and having lugs at its

upper and lower edges, a cam-roller pivoted 35
in said lugs and forming with the plate f , a
slideway, a slide g , in said slideway having
one of its ends bent forward, perforated, and
forming a shade-roller bearing, and an inde-
pendently-adjustable shade-roller supported 40
adjustably on the opposite end of the slide.

2. In a shade-roller bracket, the combina-
tion of a sheet-metal arm d , having its end
bent at right angles and the opposite margins
of said bent portions provided with forwardly- 45
projecting lugs perforated to provide bearings
to receive a cam-roller, said cam-roller pivoted
in said lugs and having a finger-piece at one
end, a strip of sheet metal adapted to slide be-
tween said cam-roller and bent portion of the 50
stem d , and having one end bent and per-
forated to receive a shade-roller pivot, and an
independent sheet-metal shade-roller support
projecting from the sliding strip on the oppo-
site side from the integral arm, said independ- 55
ent arm having a portion bent at right angles
to lie against the sliding strip and provided
with lugs reaching past the edges of said strip,
and a cam-roller pivoted in said last-mentioned lugs. 60

In testimony that I claim the foregoing I
have hereunto set my hand this 22d day of
May, 1901.

EMILE L. A. CUREAU.
